United States Patent Office.

JOHN MATTHEWS, JR., OF NEW YORK, N. Y.

Letters Patent No. 94,424, dated August 31, 1869.

IMPROVED TUMBLER-WASHER.

The Schedule referred to in these Letters Patent and making part of the same.

To all whom it may concern:

Be it known that I, JOHN MATTHEWS, JR., of the city, county, and State of New York, have invented a new and useful Improvement in Tumbler-Washers, of which the following is a full, clear, and exact description, reference being had to the accompanying drawing, forming part of this specification, and in which—

Figure 1 represents a plan of a tumbler-washing apparatus constructed in accordance with my improvement, and

Figure 2, a vertical section of the same.

Similar letters of reference indicate corresponding parts.

My invention consists in an apparatus, embracing several novel features, by which tumblers, cups, or glasses, may be washed with efficiency and despatch, both as regards their inside and outside surfaces, and under pressure of water as forced or supplied in jets, although the source from which the cleansing water is drawn gives no head or pressure.

Such apparatus will be found of great use in country and other places, where water for cleansing and other purposes is only obtainable from springs and other like sources, and will prove a great convenience in hotels and on soda-water fountains or stands.

Referring to the accompanying drawing—

A represents a basin-like base, which is designed to rest on a table, counter, or stand, and that communicates, by draining apertures *a a*, with a central discharging-chamber, B, for foul and drainage water, said chamber serving, if desired, to support the basin, also being provided with a downwardly-projecting pipe-like stem or outlet, C, preferably of cylindrical form, and that, passing through a hole in the counter, may have any suitable pipe or hose connected with it, as at *b*, for running off the escaping dirty or waste water into a bucket or other receiver, drain or channel.

A screw-thread, *c*, may be formed around this stem, at a suitable distance below the chamber B, for firmly securing the apparatus on its table or stand, by means of a nut fitted on said screw-thread, and made to bear on or against the under surface of the stand.

The base or basin A may be formed at its centre with a cylindrical upward projection, *d*, which serves as a duct for the water fouled by washing, and which may likewise serve as an exterior guide to a hollow vertical shaft or tubular column, D, that, in the operation of the apparatus, is worked up and down, and may serve the threefold purpose of forming a handle or means for working the apparatus, a support for the tumbler-guide and rest, and a duct for the water fouled in washing to escape. Said column also indirectly serves to convey up through it the water used for cleaning the tumblers.

Arranged concentrically within, or so that it pro-

jects up through the tubular stem or outlet C, and in suitable fixed connection with it, in a manner so as not to obstruct free passage down said stem, is a clean-water supply or feed-duct, E, which may be connected by a pipe or hose, at its lower end, with a bucket or other vessel containing water suitable for washing-purposes, and which carries, at its top, a valve, F, opening upward; also has screwed on to it a hollow upright stationary ram or plug, G, arranged to occupy a concentric position or thereabouts within the column D.

Fitting freely but closely, (by the aid of a stuffing-box, *s*,) around and over this stationary ram, which is left open at its top, is a vertically-reciprocating pumping barrel, H, that carries, at its upper end, a valve, I, opening outward, and is connected in any suitable positive manner with the column D, so that as the latter is worked up and down by the operator, it serves to similarly reciprocate the barrel; thus the valve I may be carried by a box, *e*, screwed into the upper end of the barrel H, and the column D be made to rest and be secured thereon by or through a tumbler-rest and guide, attached to the upper portion of the column, and clamped to or on the top of the barrel or its valve-box *e*, by a distributing cap, K, arranged to screw on to the valve-box.

Such tumbler-rest and guide, which also serves as an outside sprinkler or washer to the tumbler, may be constructed in any suitable manner, but is here shown as made up of hollow bent arms J J, of a proper curvature to receive and hold in an easy but steady manner an inverted tumbler, and in communication at their upper ends with the interior of the distributing-cap K, while their outer ends are bent upward in conformity with a basin-like construction to the top of the column D, and perforated as at *f f*.

The cap K, which is preferably made of a conical form, is also perforated, as at *g g*, to adapt it as an inside washer to the tumbler; and the upper portion of the stem of the valve I may likewise be perforated, to act in concert with the cap as a distributor of the water to the inside of the tumbler.

A spring, M, which may, if desired, be regulated by an adjustable tension-device, is introduced between the stationary ram G and upper portion of the barrel H, to support the latter with its pertaining parts and column D, and to throw them up after the same have been forced or pressed down by the hand, as applied to the column or tumbler resting on the arms J J. For this purpose, the spring M may rest upon a step formed within the stationary ram.

In using the apparatus, the tumbler is slipped upside down upon the arms J J, and the column D, with its pertaining parts, including the barrel H, rapidly worked up and down by the hand, either as applied to said column or by pressure on top of the tumbler being

washed. This gives a pumping action to the apparatus, and, by the aid of the valves F and I, causes the clean or washing water, in the upward stroke of the column D, to be sucked or drawn up the feed duct E, stationary ram G, and barrel H, and in the downward stroke of the column to be forcibly expelled through the perforations *g g* in the cap K, also aperture in the stem of the valve I, and through the perforations *f f*, in the arms J J, whereby the tumbler is most effectually washed both inside and out, and the foul or dirty water runs back down the column D, and out through the hollow stem or outlet C.

After the tumbler or tumblers have thus been washed, they may be laid, in inverted positions, on the base or basin A to drain, and the water trickling from them be run off by the apertures *a a* to the general foul-water outlet C.

A tumbler-washer constructed to operate as described, and combining, as an elementary feature, the function or action of a pump, is as cleanly as efficient, the washing water being introduced and passed off as fouled within or under cover of the operating column D. Its particular use or application, that is, in places where water under pressure is not attainable, has already or herein previously been referred to.

What is here claimed, and desired to be secured by Letters Patent, is—

1. A tumbler-washing apparatus, constructed to

operate as a pump on elevating and depressing the support which carries the tumbler, substantially as specified.

2. The combination of the stationary hollow ram G, the vertically-reciprocating barrel H, with their valves F I, the perforated distributing cap K, and the tumbler-guide and rest J J, essentially as described.

3. The tumbler-guide and rest J J, constructed to operate as an outside washer, in combination with the distributing cap K, forming an inside washer to the tumbler, the pumping barrel H, and the stationary hollow ram G, with their valves I and F, essentially as specified.

4. The combination, with the pumping barrel H, and hollow ram G, of the column D, constructed and arranged for operation in connection with the tumbler-rest and inside and outside sprinklers or washers, essentially as described, and whereby the water to be used in washing and as fouled by washing is passed within and through or under cover of said operating column, substantially as herein set forth.

5. The combination of the spring M with the reciprocating barrel H, and stationary hollow ram G, essentially as specified.

JOHN MATTHEWS, JR.
